US0D1029047S

(12) **United States Design Patent** (10) **Patent No.:** **US D1,029,047 S**
(45) **Date of Patent:** **** May 28, 2024**

(54) **VISION MODULE**

(71) Applicant: **Willand (Beijing) Technology Co., LTD.**, Beijing (CN)

(72) Inventors: **Yang Li**, Beijing (CN); **Zheng Jin**, Beijing (CN); **Lei Liu**, Beijing (CN)

(**) Term: **15 Years**

(21) Appl. No.: **35/516,472**

(22) Filed: **Feb. 6, 2023**

(80) **Hague Agreement Data**

Int. Filing Date: **Feb. 6, 2023**

Int. Reg. No.: **DM/226858**

Int. Reg. Date: **Feb. 6, 2023**

Int. Reg. Pub. Date: **Mar. 3, 2023**

(30) **Foreign Application Priority Data**

Aug. 11, 2022 (CN) 202230524841.8

(51) **LOC (14) Cl.** **15-03**

Assistant Examiner — Michael Hoffman

(57) **CLAIM**

The ornamental design for a vision module, as shown and described.

DESCRIPTION

1. Vision module

1.1 : Front

1.2 : Back

1.3 : Top

1.4 : Bottom

1.5 : Left

1.6 : Right

1.7 : Perspective

The present design shows a vision module which is used to be mounted on a self-propelled robot for visual detection.

1 Claim, 7 Drawing Sheets
